UNITED STATES PATENT OFFICE.

GAILLARD E. WEAVER AND HARRY C. BUFFINGTON, OF SPRINGFIELD, ILLINOIS, AS
SIGNORS TO WEAVER MANUFACTURING COMPANY, OF SPRINGFIELD, ILLINOIS, A
CORPORATION OF ILLINOIS.

PUNCHING AND RIVETING MACHINE.

Application filed May 20, 1927. Serial No. 192,826.

The present invention has for its leading aim and principal object the provision of an appliance adapted to exert suitable pressure for performing various operations depending upon the tools used, the apparatus being particularly adapted for employment in relining brake-bands and the like, but its desirable and satisfactory use is not limited to any particular type of work.

One salient feature of the new and improved machine is the securing of an adequate working force with the expenditure of a relatively small amount of effort on the part of the operator and the equal travel or movement of the tool on each actuation, so that, for instance, in the relining of brake-bands, the heads of all of the rivets may be countersunk like amounts.

Another characteristic of the novel appliance is that it is simple in structure and hence economical to manufacture, with small likelihood of becoming injured or impaired in ordinary service.

To enable those acquainted with this art to fully understand the invention, in the accompanying drawing, forming a part of this specification and throughout the views of which like reference characters have been used to designate the same parts, a present desirable and preferred embodiment of the invention has been shown in detail.

In this drawing:

Figure 1 is a central vertical section through the apparatus;

Figure 2 is a top plan view on an enlarged scale;

Figure 3 is a detail section of the adjustable mounting of one of the punches; and

Figure 4 is a section on line 4—4 of Figure 3.

Referring to this drawing, it will be noted that the machine includes a hollow base 11 adapted to rest on the floor and carrying an upright, tubular standard 12 to which a suitably-shaped head 13 is attached.

A horizontally-rotatable turret 14 has an outstanding lower section 15 recessed at a plurality of points 16, 16 for the accommodation of a number of dies 17, 17, and a similar upper section 18 with upright bearings 19, 19 in exact alignment or register with the correlated dies, such bearings slidingly receiving rams or plungers 20, 20

equipped at their lower ends with punches 21, 21 complementary to the associated dies. 55

The upper end of each such plunger or ram is threaded through a nut 22 and has a knurled head 23 by means of which the ram and its mating punch may be easily adjusted toward and from the companion die.

Each such nut has lateral top and bottom faces bearing on upper and lower curved surfaces 24 and 25 of the forked end 26 of one radial arm 27 of a spider or cross-head 28 mounted on the top end of a vertical, cylindrical sleeve 29 slidable in a central, upright bearing 31 in the turret, the latter having a journal 32 on its underside revolvable in a bearing in the stationary head 13, such journal being internally screw-threaded for the attachment thereto of a depending larger sleeve 34 equipped at its lower end with a centrally-apertured cup or socket member 35 screwed thereon, with a coiled spring 36 interposed between such cup and the bottom end of sleeve 29, whereby the spring tends to raise the spider or cross-head and its plurality of rams and punches. 70 75 80

A long, upright rod 37 extends through the spider 28, sleeve 29, turret 14, sleeve 34, spring 36, and cup 35, being threaded at its upper end for the reception of a nut 38 which is of sufficient size to overlap the spider, so that when the rod is pulled down 85 the spider and associated elements will be carried with it in opposition to the upwardly-pressing action of spring 36.

The lower end of pull-rod 37 has a swivel connection 39 with a lever 40 fulcrumed in the lower hollow base at 41, a link 42 joining an intermediate part of the lever to a short extension 43 on a curved, stop-arm 44 fastened to a shaft 45 oscillatory in bearings in the base 11, such shaft, outside of base, 90 also having a foot-lever or pedal 46 keyed thereto and supplied with a rearward projection 47 connected by a coiled contractile spring 48 to the shaft on which the lever 40 is mounted, whereby the spring normally lifts the pedal or treadle until the end of arm 44 strikes the top of lever 40 thus limiting such upward travel of the specified foot-operated element. 100 105

From the foregoing, it will be apparent that the two springs 36 and 48 supplement

one another in their actions, both tending to elevate the cross-head and its rams and to raise the foot-lever.

It is to be noted particularly that the link 5 42 and the short arm 43 constitute a toggle which is straightened out as the pedal is depressed, and, inasmuch as such toggle has a definite range of action when its elements are brought into alignment, a full depression 10 of the foot-lever assures that the rams and punches will descend equal amounts on each actuation, thus enabling the workman to be certain that all rivet-heads are countersunk or embedded in the brake-lining to equal 15 extents.

The operation of the apparatus will be apparent from what precedes, but it may be noted that the turret may be easily turned manually to bring any set of cooperating 20 tools to the front of the machine in position for convenient use, the cross-head, of course, turning in like degree because its rams are directly associated with the turret, and, furthermore, the pull-rod may also turn with 25 the turret due to the structure of the connection 39.

Adjustment of the punches individually may be readily effected by turning the ram 30 heads 23 and in this way the depth of punching and countersinking may be regulated as may be required by variations in the thickness of the brake-bands and the linings.

After the plungers or rams have been thus 35 adjusted for the particular work in hand, all of the holding rivets are countersunk to a uniform depth because identity or sameness of pressure is insured by the lever and toggle actions of the pedal.

The invention is not necessarily limited 40 and restricted to this particular embodiment and many mechanical changes may be incorporated therein without sacrificing any of the substantial benefits and advantages of 45 the invention and without departing from its substance or essence as defined by the appended claims.

We claim:

1. In a machine of the character described, 50 the combination of a base, a hollow standard extended upwardly therefrom, a head at the top of said standard, a turret revolvable on said head, rams slidable in bearings in said turret, a cross-head carrying said rams, a first sleeve slidable in said turret carrying said rams, a second sleeve supported by said turret and depending therefrom inside of said standard, an apertured cup on a lower part of said second sleeve, a coiled spring interposed between 55 said cup and the lower end of said first sleeve, a pull-rod connected to said cross-head and extending down through said two sleeves, spring and cup, a lever fulcrumed at its rear end in said base and having a swivel connection at its front end with said 60 65

pull-rod, a pedal outside of said base fulcrumed thereon at a higher level than the fulcrum of said lever, and a toggle connection between said pedal and an intermediate part of said lever.

2. In a machine of the character described, 70 the combination of a base, a hollow standard extended upwardly therefrom, a head at the top of said standard, a turret revolvable on said head, rams slidable in bearings in said turret, a cross-head carrying said rams, a first sleeve slidable in said turret carrying said cross-head, a second sleeve supported by said turret and depending therefrom inside of said standard, an apertured cup on a lower part of said second sleeve, a coiled spring interposed between said cup and the lower end of said first sleeve, a pull-rod connected to said cross-head and extended down through said two sleeves, spring and cup, a pedal fulcrumed on said base, a spring tending to rock said pedal upwardly, a lever fulcrumed in said base and having a swivel connection with said pull-rod, and a toggle connection between said pedal and lever.

3. In a machine of the character described, 75 the combination of a base, a hollow standard extended upwardly therefrom, a head at the top of said standard, a turret revolvable on said head, rams slidable in bearings in said turret, a cross-head carrying said rams, a sleeve slidable in said turret carrying said cross-head, a pull-rod connected to said cross-head and extending down through said sleeve, a pedal fulcrumed on said base, a spring means tending to rock said pedal upwardly, a lever fulcrumed in said base and having a swivel connection with said pull-rod, and a toggle connection between said 80 85 90 95 100

pedal and lever.

4. In a machine of the character described, 105 the combination of a supporting-frame, a turret revolvable on said frame, rams slidable in bearings in said turret, a cross-head carrying said rams, a pull-rod connected to said cross-head and extending down through said frame, a pedal fulcrumed on said frame, a spring means tending to rock said pedal upwardly, a lever fulcrumed in said frame and having a swivel connection with said pull-rod, and a toggle connection between said 110 115 120

pedal and lever.

5. In a machine of the character described, 120 the combination of a supporting-frame, a turret revolvable on said frame, individually-adjustable rams slidable in bearings in said turret, a cross-head carrying said rams, a pull-rod connected adjustably to said cross-head and extending down through said frame, a pedal fulcrumed on said frame, a spring tending to rock said pedal upwardly, a lever fulcrumed in said frame and having a swivel connection with said pull-rod, and a toggle connection between said pedal and lever.

6. In a machine of the character described, the combination of a supporting-frame, a turret revoluble on said frame, rams slideable in bearings in said turret, a cross-head carrying said rams, a pull-rod connected to said cross-head, a pedal fulcrumed on said frame, and a toggle connected between said pedal and pull-rod.

7. In a machine of the character described, the combination of a support, a turret on said support, a plurality of rams slideable in

bearings in said turret, a cross-head having open-ended slots, and nuts in said slots bearing on curved surfaces of the cross-head adjacent to said slots, said rams having screw ¹⁵ threads fitting in said nuts, whereby the rams may be easily adjusted or removed from the machine.

In witness whereof we have hereunto set our hands.

G. E. WEAVER.

HARRY C. BUFFINGTON.
